COMBINED BOTTLE AND DISPLAY CONTAINER THEREFOR

John Vincent Massey, Glencoe, and Robert Joseph Hutchcroft, Glen Ellyn, Ill., assignors to The Gillette Company, Boston, Mass.

Filed Aug. 25, 1971, Ser. No. 175,031

Term of patent 14 years

Int. Cl. D9—01

U.S. Cl. D9—12

FIG. 1 is a view in front elevation of a combined bottle and display container therefor showing our new design; FIG. 2 is a view in side elevation;

FIG. 3 is a bottom view along line 3—3 FIG. 1;
FIG. 4 is a top view along line 4—4 of FIG. 1; and
FIG. 5 is a view in section partly broken away along line 5—5 of FIG. 1.

We claim:

The ornamental design for a combined bottle and display container therefor, as shown.
